United States Patent Office.

WILLIAM CLISSOLD, OF DUDBRIDGE WORKS, NEAR STROUD, ENGLAND.

Letters Patent No. 64,077, dated April 23, 1867.

IMPROVEMENT IN FEEDING MECHANISM FOR CARDING MACHINES.

The Schedule referred to in these Letters Patent and making part of the same.

TO ALL WHOM IT MAY CONCERN:

Be it known that I, WILLIAM CLISSOLD, of Dudbridge Works, near Stroud, in the county of Gloucester, engineer, have invented "Improved Machinery for Feeding Wool and other Fibres to Preparing and Carding Machines;" and I do hereby declare that the following is a full and exact description of my said invention.

The object of this invention is to provide a means of feeding wool, cotton, or other fibrous substances to preparing or carding machines without separating the long from the short fibres. Thus, when operating with wool I propose to make a bat or sheet with the long and short wool or shoddy well mixed, and of the same consistence throughout its breadth and length. The wool or other fibre to be operated upon is placed in a large box or receiver of the width of the bat or sheet required to be made, the width being determined by the width of the machine to be fed, and by means of reciprocating-bars which form the bottom of the box it is propelled towards a horizontal opening cut in one end of the box, and corresponding in length to the width of the box. The continuous endway motion of the bars causes the wool to be discharged through the opening at a certain regulated rate, the wool passing between a pair of reciprocating combs, which, acting upon the wool, masses it into a continuous bat of uniform thickness. In the accompanying drawing—

Figure 1 is an elevation of the right side, and

Figure 2 an elevation of the left side of the feed-box, looking at it from the front.

Figure 3 is a longitudinal section of the feed-box; and

Figures 4 and 5 are respectively front and back elevations of the same.

A is a rectangular open box for receiving the wool or other material to be delivered to the preparing or carding machine to be fed. The bottom of this box is formed of inclined bars B B, which are suspended at their upper ends by hooked rods C, pendent from a round cross-bar, C¹, at the back of the box. The front and lower ends of the bars B extend to the front of the feed-box, and they are armed with steel terminations, B¹, suitably shaped, as shown at fig. 3, for propelling the wool forwards. The box A has a horizontal opening, A¹, at the level of the bars, through which the fibrous material is discharged. A forward endway motion is given alternately to every other of the bars by means of coiled springs D which connect them with a fixed cross-bar, D¹, and the return or back motion is produced by means of fingers E, or it may be on cams on a rotating transverse shaft, E¹, striking against bracket projections B² on the under side of the bars B. The object of this endway motion of the inclined bars is to feed the overlying fibre towards the horizontal opening in the front of the box and bring it under the operation of a pair of horizontal reciprocating combs or toothed bars, F, which are intended to mass it, as it is discharged from the box, into a loose, thick sheet or bat. The quantity of fibre discharged is gauged by the depth of the horizontal opening or mouth A¹. The shaft E¹, carrying the fingers E, receives motion through spur-gearing from another transverse shaft, G, which is fitted at its ends with a pair of eccentrics, (or it may be cranks,) G¹, for operating, through coupling-rods G², a pair of cranked levers, H, situate one on each side of the feed-box. These crank-rods are formed with segment racks H¹ at their outer ends for the purpose of gearing into and driving a pair of racks, F¹, attached to the comb-bars F. These comb or toothed bars slide up and down in inclined guides fitted to the front of the feed-box A, an inclination being given to them to allow each comb-bar to pass the teeth of the other as it is propelled forward. The comb-bars being thus actuated by the segment-racks through the agency of the cam-shaft and rock-levers above mentioned, they are caused alternately to act upon the fibre, giving it at the same time a slow forward motion, which motion allows of the fibres before they escape from the teeth accumulating sufficiently to form a thick, even bat. The inclined bars B, forming the bottom of the feed-box, as they are drawn back leave vacancies at their forward ends into which the fibre passes, and the tendency of the fibre as it accumulates near the discharge opening A¹ to move back at the return motion of the bars is counteracted by means of loose rods K which are pendent from a cross-shaft, L, but which are at times free to drop and bear upon the wool with their whole weight, thereby pressing it down for the ends of the bars to thrust it into the discharge opening of the feed and preventing the back motion of the bars disturbing the fibre. This cross-shaft L, which lifts the bars at the proper moment for relieving the fibre of their pressure, is carried by a pair of rock-levers, M, which are mounted on a cross-shaft, M¹, having its bearings in the sides of the box A. From the extremity of one of the levers depends a rod, N, carrying at its lower end a wedge-shaped elastic projection, N¹. A pin or projection on a

disk, O, keyed to the shaft E¹, in its rotation strikes against the elastic projection on the rod N, and thereby gives a reciprocating motion to the rock-levers M, causing them to lift the rod L, and with it the pressers K. The continuous rotation of the disk causes the elastic projection to yield to the pressure of the disk-pin, and the rod being now released the rock-levers will resume their former position and allow the rods K to press again upon the wool. The massed fibre or bat as it leaves the combs is passed between a pair of pressing-rolls, P P, which will serve to deliver it to the aprons, feed-rolls, or cylinders of the preparing or other machines. This arrangement of machinery will deliver the fibre in uniform quantity so long as there is sufficient fibre in the subse-
box to fill the discharge mouth or opening, and thus the production of even laps may be insured in the subse-
quent processes of manufacture.

Having now set forth the nature of my invention of "improved machinery for feeding wool and other fibres to preparing and carding machines," and explained the manner of carrying the same into effect, I wish it to be understood that I claim—

1. The combination, with the inclined reciprocating-bars B, of the reciprocating-comb bars F, and rods or pressers K, for the purpose of discharging the wool or other fibrous material from the feeding-box.
2. The combination, with the reciprocating-comb bars, of pressing-rolls P for delivering the wool or other fibrous material to the preparing machine in the form of a bat or sheet.

In witness whereof I, the said WILLIAM CLISSOLD, have hereunto set my hand and seal the twelfth day of November, in the year of our Lord one thousand eight hundred and sixty-six.

Signed, sealed, and delivered by the above-named WILLIAM CLISSOLD in the presence of—

WILLIAM CLISSOLD. [L. s.]
